UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

FEEDING MECHANISM FOR SEWING MACHINES.

Application filed April 19, 1921. Serial No. 462,572.

To all whom it may concern:

Be it known that I, JAMES R. MOFFATT, a citizen of the United States, residing at Chicago, in the county of Cook, State 5 of Illinois, have invented certain new and useful Improvements in Feeding Mechanisms for Sewing Machines, of which the following is a description, reference being had to the accompanying drawing and to the 10 figures of reference marked thereon.

This invention relates to new and useful improvements in feeding mechanisms for sewing machines, and more particularly to a feeding mechanism which includes a feed 15 dog mounted beneath the work support and operating through slots in the work support for engaging and feeding the material, and wherein the feed dog is carried by a feed bar attached to a feed rocker which is oscillated for imparting the feeding movements 20 to the feed dog.

An object of the invention is to provide a feeding mechanism of the above character wherein the feed rocker is oscillated by an 25 arm movably or adjustably connected thereto, which connection permits the feed rocker to be shifted for varying the working position of the fabric engaging sections of the feed dog in their respective slots.

30 A further object of the invention is to provide a feeding mechanism of the above character wherein the feed rocker may be shifted for centering the feed dog without disconnecting the actuating arm from its 35 operating means.

In the drawings which show by way of illustration one embodiment of the invention:

Figure 1 is a view in top plan of a portion 40 of a sewing machine having my improvements embodied therein and with a part of the work support broken away to show the feed dog supporting means beneath said work support;

Fig. 2 is a view partly in section and partly in elevation from the left-hand end of the machine;

Fig. 3 is a view partly in section and partly in rear elevation of the same;

Fig. 4 is a view partly in section and partly in end elevation of the parts beneath the work support;

Fig. 5 is a perspective view showing the parts separated, which operate the arm for moving the feed dog back and forth;

Fig. 6 is a section on the line 6—6 of Fig. 1;

Fig. 7 is a perspective view of the feed rocker, and

Fig. 8 is a perspective view of the feed 60 bar and feed dog carried thereby.

The invention is directed broadly to a feeding mechanism of the type wherein the feed dog is mounted beneath the work support and is provided with fabric engaging 65 sections operating through slots in the work support or throat plate forming a part of the work support. This feed dog is carried by a feed bar which is pivotally connected to a feed rocker. The feed rocker is provided with spaced supporting lugs in which 70 is mounted a bar or shaft to which the feed bar is fixedly connected. This bar or shaft is secured from endwise movement in the lugs by suitable means and the bar or shaft 75 may be adjusted laterally in the lugs for positioning the feed bar so that the fabric engaging portions of the feed dog will be located centrally of the slots in which they work. The feed rocker is oscillated by an 80 arm which is formed integral with a short stud which in turn is clamped in a split sleeve formed as a part of the feed rocker. This arm is connected by means of a link to an adjustable crank pin on the end of the 85 main shaft. By loosening the connection of the arm to the feed rocker, said feed rocker may be moved forwardly or rearwardly and the working position of the feed dog shifted, and thus the working stroke of the feed dog 90 centered relative to the longitudinal length of the slots in the throat plate forming a part of the work support, and this shifting of the feed rocker to center the feed dog is 95 accomplished without disconnecting the arm from its actuating means.

Referring more in detail to the drawings, my improved feeding mechanism is shown as applied to a sewing machine having a supporting bed 1 carrying a work support 2 to which is attached a throat plate 3. This throat plate is provided with needle openings 4, 4 and with three feed slots 5, 6 and 7. The feed dog indicated at 8 is provided with fabric engaging sections 9, 10 105 and 11 which work respectively in the slots 5, 6 and 7. The feed dog 8 is carried by a feed bar 12 which is provided with a laterally projecting arm 13 and spaced sleeves 14, 14. The feed bar is raised and lowered by 110

an eccentric 15 on the main shaft 16. At the rear of the machine there is a feed rocker 17. This feed rocker as clearly shown in Fig. 7 is provided with two downwardly extending sleeves 18, 18 and two upwardly extending sleeves 19, 19. A shaft 20 extends through the sleeves 18, 18 and is mounted in bearing lugs 21, 21 carried by the bed plate 1 of the machine. Collars 22, 22 are secured 10 to the ends of the shaft 20 by set screws 23, and said collars bear against the outer faces of the sleeves 19, 19. The feed rocker is secured to the shaft 20 by set screws 24. The distance between the outer faces of the 15 sleeves 18, 18 is slightly less than the distance between the inner faces of the bearing lugs 21, 21. Mounted in the sleeves 19, 19 is a shaft 25. This shaft also extends through the sleeves 14, 14 which are secured 20 to the shaft by means of set screws 26. The shaft 25 is held from endwise movement in the sleeves 19, 19 by means of collars 27, 27 which are secured to the shaft 25 by set screws 28, 28. The distance between the 25 inner faces of the sleeve bearings 19, 19 is slightly greater than the distance between the outer faces of the sleeves 14. By shifting the shaft 25 or the shaft 20 endwise, the feed bar may be moved bodily laterally, and 30 thus the fabric engaging sections of the feed dog centered relative to the transverse width of the feed slots. This features, per se, forms no part of the present invention, but is shown, described and claimed in my co-pending application, Serial No. 462,571 filed 35 of even date herewith.

The feed rocker is oscillated for imparting feeding movements to the feed dog by means of an arm 29. This arm is provided 40 with a stud 30 which is preferably formed integral with the arm. The stud 30 is adapted to enter a split sleeve 31 preferably formed integral with the feed rocker 17. Said split sleeve is clamped on to the stud 45 by means of screws 32, 32. This serves as a means for rigidly securing the arm 29 to the feed rocker. By loosening the screws 32, the feed rocker may be shifted forwardly or rearwardly, the stud 30 turning in said 50 sleeve 31.

On the end of the main shaft 16 there is a disk 33 which is provided with a diametrically arranged T-slot 34. Located in this 55 T-slot is a block 35 which carries the crank pin 36. Said block may be shifted in the slot by means of an adjusting screw 37. On the crank pin is placed a sleeve 38 which is free to oscillate on said crank pin. A 60 link 39 is provided with a cylindrical opening 40 adapted to receive the sleeve 38 and clamping screw 41 serves to cause the link to firmly grip the sleeve. Said link 39 is provided with spaced sections 42, 42 between 65 which the end of the arm 29 extends and a pivot pin 43 carried by the spaced sections

42 of the link serve as a pivotal connection between the link 39 and the arm 29.

As the main shaft rotates, the crank pin 36 through the link 39 will oscillate the arm 29, and this in turn will oscillate the 70 feed rocker 17. The oscillating movements of the feed rocker through the feed bar are imparted to the feed dog and thus the feed dog is given its feeding movements. It will readily be seen that when the connection between the arm 29 and the feed rocker is 75 loosened, the feed rocker may be shifted forwardly or rearwardly, which will shift the feed dog either forwardly or rearwardly to a new working position. Thus it is that 80 the working position of the fabric engaging sections of the feed dog may be centered relative to the length of the feed slots in which they operate.

Then again, by loosening the collars 22, 22, the shaft 20 may be moved endwise which will bodily shift the feed rocker for laterally centering the feed dog in the feed slots as has been described above. The stud 30 may be readily shifted endwise in the sleeve 90 31 so as to accommodate itself to the new position of the feed rocker, and thus the arm 29 can remain in proper position so as to actuate the feed rocker without any binding of the parts and yet permit this bodily shifting of the feed rocker for centering the feed dog. 95

It is obvious that minor changes in details of construction may be made without departing from the spirit of the invention as 100 set forth in the appended claims.

Having thus described the invention, what I claim as new and desire to secure by Letters-Patent, is:—

1. In a sewing machine, the combination 105 of a work support having feed slots and a feeding mechanism including a feed dog having fabric engaging sections working in said slots, a feed bar to which said feed dog is attached, means for raising and lowering said feed bar, a feed rocker to which said bar is connected, an arm, means for connecting said arm to the feed rocker, and means for oscillating the arm for imparting feed movements to the feed dog, said connecting 110 means for the arm and rocker being such as to permit the working position of the feed rocker to be shifted forwardly or rearwardly for centering the feed dog lengthwise of the feed slots the length of the stroke 115 remaining the same.

2. In a sewing machine, the combination 120 of a work support having feed slots, and a feeding mechanism including a feed dog having fabric engaging sections working in said slots, a feed bar to which said feed dog is attached, means for raising and lowering said feed bar, a feed rocker to which said feed bar is connected, an arm, said arm having a projecting stud, a split sleeve carried 125 130

by the feed rocker in which said stud is adjustably held whereby the feed rocker may be shifted forwardly or rearwardly, and means for oscillating the arm for imparting feed movements to the feed dog.

3. In a sewing machine, the combination of a work support having feed slots, a feeding mechanism including a feed dog having fabric engaging sections working in said slots, a feed bar to which said feed dog is attached, means for raising and lowering said feed bar, a feed rocker to which said bar is connected, an arm, said arm having a projecting stud, a split sleeve carried by the feed rocker in which said stud is adjustably held whereby the feed rocker may be shifted forwardly or rearwardly through the shifting of the connection of the arm to the feed rocker, a main shaft, a crank on the main shaft, and a link connecting the crank to the free end of the arm for oscillating said arm for imparting back and forth movements to the feed dog.

4. In a sewing machine, the combination of a work support having feed slots, a feeding mechanism including a feed dog having fabric engaging sections working in said

slots, a feed bar to which said feed dog is attached, means for raising and lowering said feed bar, a feed rocker to which said bar is connected, an arm, said arm having a projecting stud, a split sleeve carried by the feed rocker in which said stud is adjustably held whereby the feed rocker may be shifted forwardly or rearwardly through the shifting of the connection of the arm to the feed rocker, a main shaft, a crank on the main shaft, a link connecting the crank to the free end of the arm for oscillating said arm for imparting back and forth movements to the feed dog, a shaft on which said feed rocker is rigidly mounted, means whereby said shaft may be shifted endwise for shifting the feed dog laterally to position the fabric engaging sections thereof centrally of the feed slots, the adjustable connection between the stud and the split sleeve permitting said sleeve and stud to have an endwise relative movement whereby said feed rocker may be shifted laterally without causing the connection of the arm to the operating mechanism therefor to cramp or bind.

In testimony whereof, I affix my signature.
JAMES R. MOFFATT.
